UNITED STATES PATENT OFFICE.

FERNAND PERRIN, OF VOLVIC, FRANCE.

CONCENTRATION OF SULFURIC ACID.

1,301,598.

Specification of Letters Patent. Patented Apr. 22, 1919.

Application filed February 7, 1919. Serial No. 275,654.

To all whom it may concern:

Be it known that I, FERNAND PERRIN, citizen of the French République, residing at Volvic, Puy-de-Dôme, France, have invented 5 certain new and useful Improvements in the Concentration of Sulfuric Acid, of which the following is a specification.

This invention relates to improvements in apparatus for the concentration of sulfuric acid, and more particularly in those made of lava or Volvic stone or pottery and comprising a saturator and a regenerator.

The improvements chiefly relate to the circulation of hot gases in the saturator, 15 which circulation is effected with increased contact of the gases with the acid and consequently utilizes better the heat of the said gases, besides economizing fuel and giving a better and quicker concentration.

20 The invention also relates to the regenerator which is provided with openings for cleaning, windows and grooves or conduits provided at the bottom surface of the plates and producing a better working owing to an 25 easier cleaning of the apparatus and an improved circulation of the hot gases.

These improvements are illustrated by way of example in the accompanying drawings in which:

30 Figure 1 shows in plan the construction of one of the plates of the regenerator,

Fig. 2 is a sectional plan showing the saturator,

Fig. 3 is an elevation in section on the 35 line B—B of Fig. 2 and

Fig. 4 an elevation in section on the line A—A of Fig. 2.

In the said apparatus, the saturator 1 is of 40 a rectangular shape, made of lava, pottery or an agglomerate resisting the action of sulfuric acid even when hot, joined together and calked. In the interior of the said saturator are placed two longitudinal divisions 2, 3, also of refractory material, which divide the interior of the saturator into three parts, the central part called the gas flue, and the two lateral parts called the spluttering flues.

45 The gases coming from the producer, are drawn in by means of a special fan or blower and enter the apparatus through the central flue 4, their progress toward the outlet is stopped by a baffle plate 5 which forces them to pass under each division and into the spluttering flues, but even there the baffle plates 6, 7, prevent them from continu-

ing to follow their path and force them to pass for the second time through the longitudinal divisions, the gases passing again into the central flue where the stone 8 (Fig. 60 3) arranged on the longitudinal divisions and under the regenerator, forces them to pass again under the divisions for the third time, so that the gases arrive in the spluttering flues 9, 10, once more.

65 In Fig. 2 the arrows show clearly the path followed in the saturator by the gases which, from their admission to their escape from the saturator, remain in thorough contact with the acid to be concentrated.

70 The baffle plates 5, 6, 7, project to a few centimeters into the acid, so as to make a hydraulic joint, this insures that the gases cannot circulate under the baffle plates while they pass under the divisions.

75 The acid outlet pipe is provided with a sluice valve 11, Fig. 3, by means of which the level of the acid in the saturator can be regulated. This pipe is arranged so as to enable the saturator to be drained by removing the said valve, a hole 12 provided in one of the bottom stones and facing one of the inspection windows 13, enables all mud or other deposit that may have collected during the working, to be completely expelled by 80 means of a siphon.

85 The windows 13 arranged at each side of the saturator and those 14, 15 provided under the regenerator, are for the purpose of removing any sulfates of iron that may 90 have been produced in the form of crystals along the longitudinal divisions or under the plates in the spluttering flues 9, 10. This novel construction makes a quick and thorough cleaning of the apparatus possible.

95 On leaving the saturator, the hot gases are drawn into a regenerator which, among other advantages, presents that of doing away with the use of porcelain or other parts intended to retain the gases in contact 100 with the acid. The plates 17 constituting the regenerator, are in one or more parts, and their dimensions vary to suit the size of the apparatus, they are provided at the bottom part with bosses or projections, the object of which is to keep back the gases and to prevent them from circulating too quickly from a lower plate to an upper one. Each boss is also provided with a longitudinal V-shaped groove 16, the object of which is 110 to form an obstacle to an excessively quick traveling of the gases which are thus main-

tained in thorough contact with the acid to be concentrated which is in the cup formed by the upper part of the plate.

Cleaning holes 18 provided half in an upper plate and half in a lower plate, make possible a quick and thorough cleaning of each plate. Expulsion of the deposits can be effected from the saturator through the openings 19 which form a passage for the 10 gases drawn into the condenser and to the acid to be concentrated.

With the apparatus described, it is possible to obtain a regular and easy production of an acid concentrated to 97-98% 15 H_2SO_4 with a minimum consumption of fuel.

What I claim as my invention and desire to secure by Letters Patent is:—

In an apparatus for the concentration of

sulfuric acid the combination with a regenerator and a saturator, of longitudinal partitions in said saturator dividing the same into a plurality of flues, *i. e.*, a central flue and lateral flues, a baffle plate projecting into the central flue so as to force the hot 25 gases to pass under the said partitions into the lateral flues, baffle plates projecting into the lateral flues, forcing the hot gases to pass under the said partitions back into the central flue, and a means for forcing the hot 30 gases back once more into the lateral flues.

In testimony whereof I have signed my name to this specification in the presence of two subscribing witnesses.

FERNAND PERRIN.
